UNITED STATES PATENT OFFICE

RAMON GARCIA MOYA, OF CORNELLA DE LLOBREGAT, SPAIN

SHUTTLELESS LOOM

Application filed November 22, 1927, Serial No. 235,088, and in Spain November 24, 1926.

This invention relates to shuttleless looms of the type described in my co-pending application Serial No. 256,349, filed February 23, 1928, or other similar types in which 5 the weft passes from a bobbin mounted upon the frame of the loom, on one side of the latter, and is inserted into the shed by means of a weft carrying arm given a to and fro movement, which arm passes the weft double 10 from one side of the cloth to the other and is withdrawn after the loop or bend in the double weft has been retained by a suitable mechanism. In this type of loom the best means for retaining the weft in the selvedge 15 opposite the one at which it is inserted, is to dispose at this part of the loom, as already indicated in the said application, a mechanism provided with a bobbin similar to the central bobbin in sewing machines, by which 20 mechanism the thread from this bobbin itself is made to pass through the loop or bend in the weft. In this way the thread of the bobbin is incorporated in the cloth as if it were the last thread of the warp beam and 25 there is formed at this edge of the cloth a perfect selvedge exactly equal to that which is formed at the edge at which the weft is inserted.

This invention comprises a bobbin mechanism of this kind which presents the advantages of being simple in construction and operating with great accuracy and perfection, leaving the selvedge perfectly formed.

In the accompanying drawings are illustrated the necessary parts of a shuttleless loom provided with the mechanism forming the subject of this invention.

Fig. 1 is a view from above of the mechanism forming the selvedge and of the end of the 40 weft carrying arm when it reaches the end of its travel, that is to say at the moment when the selvedge forming mechanism catches the weft thread.

Fig. 2 is a vertical section taken along the 45 line II—II in Fig. 1.

Fig. 3 is a view from above which is similar to Fig. 1, but in the position for which the weft carrying arm commences its return stroke and the selvedge forming mechanism 50 has rotated through 180° and is passing the

thread from the bobbin through the loop in the weft thread.

Fig. 4 is a vertical section taken along the line IV—IV in Fig. 3.

In Figs. 1 to 4, 1 indicates in general the 55 selvedge forming mechanism which is mounted at the end of a bar 2 parallel to the breast beam of the loom, which bar also carries the temples for maintaining the convenient width of the cloth. 3 is the weft carrying arm which inserts the weft 4 into the shed, which arm is provided at its end with a hole 5 through which passes constantly the weft thread and comprises immediately behind this hole a recess 6. In this recess 6 the weft 60 thread 4 is completely free and consequently in a favourable position to be caught by the selvedge forming mechanism.

The selvedge forming mechanism comprises a hollow box or drum 7 which is adapted to turn freely in the frame 1 of the mechanism and this drum 7 comprises at each side flanges 8 and externally to one of these flanges a toothed crown 9 which engages with a wheel 10 mounted upon the end of a shaft 70 11 which is given a suitable movement of rotation by means of a sprocket wheel 12 and a chain drive. In the interior of the rotatable drum 7 is housed a bobbin 13 provided with a certain quantity of thread 75 which is that which has to become entwined with the turn of loop in the weft 4.

The flange 8 of the drum 7 comprises at a suitable point on its circumference, an extension or tooth 14 adjacent to a notch 15 80 which extends so as to form between the teeth of the toothed crown 9 a small cavity or channel 16 which extends over the whole width of the rotatable drum 7 and in which can enter the weft thread 4 in such a way that when the weft thread is lodged in this channel the drum 7 can turn compelling the weft thread to pass between the drum and the frame or support 1. This frame 1 also comprises an open part 17 coinciding with the weft carrying arm 3 so that the weft thread can pass through the notch 15 in the channel 16.

The toothed wheel 10 and consequently 90 the drum 7 rotate continuously, but their 100

movement is synchronized in such a way with the general movement of the loom and consequently with the movement of the weft carrying arm 3 that, when this arm reaches 5 the end of its travel, that is to say is in the position shown in Fig. 1, the tooth or extension 14 on the drum 7 arrives in the position shown in Fig. 2 and is rotated with the drum 7 in the direction of the arrow 18 so that 10 the tooth 14 is introduced into the notch 6 in the weft carrying arm and catches the front end of the weft 4 compelling it to enter the notch 15 and the channel 16.

When the weft thread has arrived in this 15 position, the movement of rotation of the drum 7 continuing, this weft thread turns around the drum 7, as shown in Figs. 3 and 4, while the weft carrying arm is withdrawn, and as a result of this rotation of the weft 20 thread 4 about the bobbin 13, the thread 19 of the latter is passed through the turn or loop in the weft 4.

The movement of rotation of the drum in the direction of the arrow 18 continuing, 25 a moment arrives when the weft thread 4 escapes from the drum 7 and then the movement of the weft carrying arm 3 in the last stage of its backward movement, pulls this weft thread, the thread thus remaining conveniently held in the shed and arranged for 30 the healds of the loom to operate and produce the counter shed, and the said operations can then take place again.

I claim:-

35 In a shuttleless loom of the type described, in which the weft is inserted by a reciprocating weft carrying arm the combination of a selvedge forming mechanism comprising a continuously rotating drum, 40 said drum having a toothed crown, a toothed pinion, meshing with the toothed crown of said drum, a thread bobbin in said drum, a weft engaging finger on the drum projecting tangentially from the drum and adapted 45 to catch the loop of the weft inserted by the weft carrying arm and a channel in said drum to receive this weft thread and carry said thread around the bobbin, said drum being rotated in timed relation with respect 50 to the movement of the weft carrying arm, whereby when said weft-carrying arm reaches the end of its travel the tooth of the drum catches the weft thread carried by the arm.

In testimony whereof I have signed my 55 name to this specification.

RAMON GARCIA MOYA.
